UNITED STATES PATENT OFFICE

2,531,643

TROTLINE HANGER

Tom Pringle, Ardmore, Okla.

Application December 12, 1946, Serial No. 715,788

2 Claims. (Cl. 43—54.5)

1

The present invention relates to new and useful improvements in fishing equipment and more particularly to a hanger for the hooks of a trot line to support the line in a position to prevent fouling of the hooks and line with objects when the line is being pulled into a boat or being paid out therefrom.

An important object of the present invention is to provide a portable detachable holder of this character including means for easily and quickly clamping the holder to a part of the boat.

Another object of the invention is to provide a holder of this character including a hook supporting arm by means of which the hooks and line may be suspended therefrom in a manner to provide for the quick drying of the line.

A still further object is to provide a shield placed over the hooks after being suspended from the supporting arm to prevent injury to persons by the hooks.

A still further object is to provide a device of this character adapted for the purposes for which the same is intended.

Other objects and advantages reside in the details of construction and operation as more fully hereinafter described and claimed, reference being had to the accompanying drawings forming a part hereof, wherein like numerals refer to like parts throughout, and in which—

Figure 1 is a side elevational view.

Figure 2 is an elevational view taken at 90° from Figure 1 and looking toward the rear end of the hook supporting arm.

Figure 3 is a transverse sectional view taken on a line 3—3 of Figure 2.

Figure 4 is a fragmentary vertical sectional view taken on a line 4—4 of Figure 2, and

Figures 5 and 6 are transverse sectional views of the hook supporting arm taken respectively on the line 5—5 and 6—6 of Figure 1.

Referring now to the drawings in detail wherein for the purpose of illustration I have disclosed a preferred embodiment of the invention, the numeral 5 designates a horizontal supporting bar positioned between the sides of a channel 6 formed at the back of a C-clamp 7, the bar 5 being secured in the channel by bolts and nuts 8. The clamp 7 includes a clamping screw 9 threaded through one end thereof for securing the clamp in an inverted position to a suitable supporting structure, such as the gunwale of a boat (not shown).

A pair of posts 10 of strap metal or the like, have their lower ends welded or otherwise suitably secured to the bar 5 and extend upwardly

2

therefrom in spaced parallel relation to each other. Braces 11 extend upwardly from the outer ends of the bar 5 to the upper portion of the posts 10.

The horizontal hook supporting arm 12 has its inner end positioned between the posts 10 and is pivotally connected thereto by means of a bolt and nut 13 for vertical swinging movement into and out of a folded position parallel to the posts, the outer end of the arm 12 being supported by an inclined folding brace 14. A disengageable ball and socket connection 15 is provided between the upper end of the brace and the underside of the arm to quickly release the arm and the lower end of the brace 14 is connected to the posts 10 by means of a pivoted substantially U-shaped wire bail 16 to also enable the brace to be folded parallel to the posts 10.

The arm 12 is formed with a flat vertical surface 17 at one side while the opposite side of the arm 12 tapers gradually toward its upper edge as shown at 18 and over which the bill portion 19 of a fish hook is engaged with the shank 20 positioned against the flat side 17 of the arm. The barb 21 of the hook rests against the tapered portion 18 of the arm inwardly of the side of the arm whereby to prevent the barb from projecting outwardly at the side of the arm and thus avoid entanglement with objects which might come into contact with the arm.

A shield 22 constructed of an elongated strip of metal includes a flat portion 23 positioned outwardly of the shank 20 of the hook at the flat side of the arm 12, the upper edge of the shield 22 being curved over the upper edge of the arm and over the bills 19 of the hooks as is shown at 24, to secure the hooks in position on the arm. The lower edge of the shield is formed with inwardly projecting tongues 25 engaging the underside of the arm 12 to function as clips with the upper curved edge 24 of the shield to secure the shield in position on the arm. The shield 22 and arm 12 are detachably connected to posts 10 by means of bolt and nut 13. The fish line 26 to which the hooks 20 are attached is suspended in position below the arm 12 to prevent entanglement of the line while the line is being pulled in or payed out from the boat and when the line 26 and hooks 20 are supported on the arm 12, the line will be quickly dried to prevent rotting thereof.

From the foregoing it will be apparent that the clamp 7 may be easily and quickly secured in position to a part of a boat for supporting the post 10 in an upright position and with the arm 12 projecting horizontally from one side of the

post and on which the fish hooks may be conveniently placed and easily removed therefrom.

When the device is not in use, brace 14 is released from arm 12 and the latter is swung downwardly between the posts 10, while the arm 12 and shield 22 are swung upwardly and then downwardly against the posts, in a position parallel thereto for conveniently carrying the device in a compact form.

In view of the foregoing description taken in conjunction with the accompanying drawings it is believed that a clear understanding of the construction, operation and advantages of the device will be quite apparent to those skilled in this art. A more detailed description is accord- 15 ingly deemed unnecessary.

It is to be understood, however, that even though there is herein shown and described a preferred embodiment of the invention the same is susceptible to certain changes fully comprehended by the spirit of the invention as herein described and the scope of the appended claims.

I claim:

1. A fish line holder comprising an upstanding member, attaching means therefor, an arm 25 at the upper end of the member for hanging fish hooks thereon, a shield including a clip and a

bolt, said bolt and clip detachably connecting the shield to the arm in a position for covering the hooks.

2. In combination, a fish line holder including 5 an upstanding member having a fish hook engaging arm at its upper end, an elongated horizontal bar at the lower end of the upright member, braces between the ends of the bar and the upright, said arm being foldable against the upright, a folding brace between the upright and the arm, and an attaching clamp secured to the underside of the bar.

TOM PRINGLE.
